CORNER CONSTRUCTION FOR METAL
FURNITURE

John H. Page, Muskegon, Mich., assignor to The
Shaw-Walker Company, Muskegon, Mich., a
corporation of Michigan

Application December 24, 1938, Serial No. 247,629

6 Claims. (Cl. 189—36)

This invention relates to improvements in metal furniture construction, and more particularly to the construction of molded and rounded corners for cabinets, desks, pedestals and the like.

Sheet metal furniture, cabinets and the like having rounded corners have heretofore been constructed by the use of large and costly dies which draw and form entire panels into a pan shape having the desired contour. These panels are then assembled with other curved or flat sheets by overlapping and welding or by butt-welding to form the completed cabinet shell. This method is economical and practical only 10 when the product has such a wide use as to permit its manufacture in great quantities.

By another method such corners have been made by constructing angle corners, filling the interior with welding material and then grinding 20 and filing the exterior corners until they assume the desired roundness. This latter method is apt to result in imperfect corners and is too crude to be used on products requiring fine workmanship and appearance. The hand labor required 25 also makes for relatively high production cost.

The object of the present invention is to provide a rounded corner comprised of flat, formed and drawn pieces of sheet metal which, when spotwelded together by the usual methods used 30 in sheet metal furniture construction, form a molded, rounded corner of pleasing appearance and possessing great strength and rigidity.

Another object of the invention is to provide a corner of the kind comprised of parts which 35 may be made without the use of expensive drawing dies and which may be assembled and secured together at a minimum of cost.

The advantages of the invention will appear more fully as I proceed with my specification.

40 In the drawings:

Figure 1 is a perspective view of an end of a piece of furniture, as for example, a desk provided at the bottom with a corner construction embodying the invention.

45 Figure 2 is a perspective view on an enlarged scale showing the improved corner construction as looked at from below and forward of the bottom corner of the desk in which it is embodied.

Figure 3 is a view in perspective showing in 50 disassembled relation the several elements which, when secured together, form the improved corner construction as looked at from the interior of the corner.

Figure 4 is a perspective view looked at from 55 the outside of the corner, showing the several

elements of the corner in partially assembled relation.

Figure 5 is a perspective view looked at from the inside showing the several elements assembled to form the corner. 5

Figure 6 is a perspective view looked at from the interior, showing the elements of the corner assembled and secured to the side and bottom panel plates which form the body of the piece of furniture. 10

Figure 7 is a perspective view looked at from the interior, with the three angle plates included in the corner connected by miter-joints and with the corner piece itself omitted.

Figure 8 is a perspective view showing one of 15 the angle plates with mitered ends.

Figure 9 is a perspective view looked at from the interior of the parts comprising the corner 20 disassembled relation, with two of the angle plates made integral with the bottom panel plate.

Figure 10 is a perspective view showing a modified form of the corner construction as it appears when looked at from the exterior.

Figures 11 and 12 are, respectively, inner and 25 outer perspective views of the corner piece used in the modification shown in Figure 10.

Referring now to that embodiment of the invention illustrated in the drawings, and particularly Figures 1 to 6, inclusive: 15, 16 and 17 indicate, respectively, sheet metal panels disposed at angles, in this case right angles to each other and forming upright adjacent side, end and bottom walls of a piece of furniture, as a desk. A indicates a vertical angle plate to which the 30 vertical panels 15 and 16 are secured; B indicates a horizontal angle plate to which the vertical panel 15 and the horizontal bottom panel 17 are secured; and C indicates a horizontal 35 angle plate to which the vertical panel 16 and the horizontal panel 17 are secured,—the three angle plates being each disposed at angles to the other, like to those between the said panels, in this case right angles. Each of said angle plates A, B and C is made from a flat strip of metal and is formed 40 at the angle with a longitudinally extending, preferably rounded bead,—a, b and c, respectively. Said bead is upset from the angle plate to present lateral shoulders D, D rising from the 45 adjacent faces of the angle plate.

The angle plates A, B and C are so formed and cut that when brought together at the predetermined angles, the lateral vertical edges 18, 18 of the angle plate A will abut the vertical end edges 19, 20 of the angle plates B and C, re- 50, 55

- spectively; and the mitered edges 21, 22 of the bottom flanges of the angle plates B and C will abut each other,—the parts being so cut and relatively disposed as to leave an opening at the junction of the three angle plates. This gap or opening is closed by a corner piece E, which is drawn from sheet metal into trihedral form, with its faces disposed as shown at right angles to each other, and of such size that its faces overlap the marginal proximate ends of the angle plates as shown in Figures 3, 4 and 5. It is made at the angles and at the apex of said angles to conform to and merge into the beads a, b and c of the angle plates, being rounded in this case as are said beads. It has transverse ends 23, 23 at the angles between its faces, which ends are formed to abut the proximate ends of the beads a, b, c of the angle plates when in assembled relation with the angle plates A, B and C.
- 20 And the non-abutting ends 18^x, 21^x, 22^x of the flanges of the angle plates overlapped by said corner piece are formed in arcs to follow closely the arcs between the vertical and horizontal branches of the rounded edges of said corner piece, in such manner as to continue and merge the beads of said vertical and horizontal angle plates, as shown in Figure 2.

The above described assembly is clearly shown in Figure 3, where the corner piece E appears assembled with the angle plate B; in Figure 4 where it appears in process of assembly with the angle plates A and B; and in Figure 5 where it appears in complete assembled relation with the angle plates A, B and C.

35 From an observation of Figure 2 it will be seen that the beads a, b and c of the angle plates flow into and merge with the rounded edges at the angles of the corner piece E, and that the rounding of said piece E at the point where said beads a, b and c would intersect if continued, produces a rounding finished flow of metal in all directions, with the edges 18^x, 21^x and 22^x of the angle plates continuing and merging with the beads a, b and c. This produces a finished and slightly construction when the four pieces are welded together in such assembled relation.

The upright panels 15, 16 and the bottom panel 17 are welded to the flanges of the several angle plates A, B and C, preferably to their inner faces, 50 and are cut away at 15^a, 16^a, 17^a short of the corner piece E, as shown in Figure 6.

In the construction shown in Figures 1 to 6, inclusive, the abutting end edges of the bottom flanges of the angle plates B and C are shown 55 formed to make a miter-joint. In the modification shown in Figure 7, the abutting edges 18^a, 18^a of the angle plate A and the associated edges 19^a, 20^a of the angle plates B and C are likewise formed to make miter-joints in each case.

60 The panels as heretofore described are each separate pieces of sheet metal, which are rigidly secured to the angle plates by welding or otherwise, as hereinbefore described. But without seriously complicating or increasing the expense of forming and drawing, a panel may be made integral with two angle plates, or one angle plate may be made integral with two panels. An example of the first mentioned is shown with the parts in expanded relation in Figure 9. Here A¹, B¹ and C¹ indicate the angle plates, and E¹ indicates the corner piece. 17^x indicates the bottom panel, which is integral with the bottom flanges of the bottom angle plates B¹, C¹. Here the bottom plate 17^x has a curved edge 17^y which takes 75 the place of and performs the bead-continuing

function of the edges 21^x, 22^x of the bottom flanges of the angle plates B and C, as shown in Figure 3.

Obviously the form or the offset of the bead provided at the angle of the angle plates or of the corner pieces to correspond therewith, may be varied without departing from the spirit of the invention. In Figures 10, 11 and 12 is illustrated a bead which is offset at its edges at a greater distance than the thickness of the sheet metal from which the angle plates are formed or drawn. 15^z, 16^z, 17^z indicate the panels; A^z, B^z, C^z indicate the angle plates; E^z indicates the corner piece. a^z, b^z, c^z indicate the respective beads at the angles of the angle plates. In this case, however, the beads are offset at their lateral edges D^z at a greater distance from the faces of the angle plates, the inner faces as shown, than the thickness of the metal of which the angle plates are made.

20 The corner piece E^z is formed to provide bosses or shoulders e^z which project from its main surface and are formed to follow the rounded edges 18^z, 18^z and 21^z, 22^z of the angle plates A^z, B^z and C^z to form a continuous flush surface of the 25 molded portion around the corner, as shown in Figure 10.

While in describing my invention I have referred to several details of construction and arrangement of parts, it will be obvious that they 30 are capable of some modifications and changes without departing from the spirit of the invention which is not limited thereto except as may be pointed out in the appended claims.

I claim as my invention:

35 1. A sheet metal corner construction connecting three panels disposed at an angle to each other, comprising three angle plates each common to two adjacent panels, each angle plate being formed at the angle with a bead having upset lateral edges and an end edge terminating short of said corner, said angle plates being formed at their proximate ends with complementary abutting edges, leaving an opening about the corner, and a trihedral corner piece closing 40 said opening, said corner piece being formed at its angles in approximate conformity to said beads and having edges which abut the end edges of said beads, and said angle plates overlapping said corner piece and being formed in arcs to follow the arcs between the vertical and horizontal branches of the rounded edges of said corner piece.

45 2. A sheet metal corner construction connecting three panels disposed at right angles to each other, comprising three angle plates each common to and secured to the outer faces of two adjacent panels, each angle plate being formed at the angle with a bead having lateral edges upset from the inner faces of said angle plates and an 50 end edge terminating short of the apex of said corner, said angle plates being formed at their proximate ends with complementary abutting edges, leaving an opening about the corner, and a trihedral corner piece closing said opening and 55 overlapping the proximate end margins of said angle plates, said corner piece being formed at its angles in approximate conformity to said beads and having edges which abut the end edges of said beads.

60 3. A sheet metal corner construction connecting three panels disposed at right angles to each other, comprising three angle plates each common to and secured to the outer faces of two adjacent panels, each angle plate being formed at 65

the angle with a bead having lateral edges upset from the inner faces of said angle plates and an end edge terminating short of the apex of said corner, said angle plates being formed at their proximate ends with complementary abutting edges, leaving an opening about the corner, and a trihedral corner piece closing said opening and overlapping the proximate end margins of said angle plates, said corner piece being formed at its angles in approximate conformity to said beads and having edges which abut the end edges of said beads, and said angle plates overlapping said corner piece and being formed in arcs to follow the arcs between the vertical and horizontal branches of the rounded edges of said corner piece.

4. A sheet metal corner construction connecting three panels disposed at right angles to each other, comprising three angle plates each comprising 5 mon to two adjacent panels, some of said angle plates and panels being integral with each other, each angle plate being formed at the angle with a bead having upset lateral edges and an end edge terminating short of said corner, said angle plates being formed at their proximate ends with complementary abutting edges, leaving an opening about the corner, and a trihedral corner piece closing said opening, said corner piece being formed at its angles in approximate conformity to said beads and having edges which abut the end edges of said beads, and said angle plates overlapping said corner piece and being formed in arcs to follow the arcs between the vertical and horizontal branches of the rounded edges of said corner piece.

5. A sheet metal corner construction comprising three angle plates, each angle plate being formed at the angle with a bead having upset lateral edges and an end edge terminating short of said corner, said angle plates being formed at their proximate ends with complementary abutting edges, leaving an opening about the corner, and a trihedral corner piece closing said opening, 10 said corner piece being formed at its angles in approximate conformity to said beads and having edges which abut the end edges of said beads, and said angle plates overlapping said corner piece and being formed in arcs to follow the arcs between the vertical and horizontal branches of the rounded edges of said corner piece.

6. A sheet metal corner construction comprising three angle plates, each angle plate being formed at the angle with a bead having lateral edges upset from the inner faces of said angle plates, and an end edge terminating short of the apex of said corner, said angle plates being formed at their proximate ends with complementary abutting edges, leaving an opening about the corner, and a trihedral corner piece closing said opening and overlapping the proximate end margins of said angle plates, said corner piece being formed at its angles in approximate conformity to said beads and having edges which abut the end edges of said beads.

JOHN H. PAGE.
